UNITED STATES PATENT OFFICE.

GEORGE BORST AND FREDERICK WILL, OF ROCHESTER, NEW YORK.

FIRE-ESCAPE.

SPECIFICATION forming part of Letters Patent No. 289,061, dated November 27, 1883.

Application filed October 22, 1883. (No model.)

To all whom it may concern:

Be it known that we, GEORGE BORST and FREDERICK WILL, both of the city of Rochester, in the county of Monroe and State of New York, have invented a certain new and useful Improvement in Fire-Escapes; and we do hereby declare that the following is a full, clear, and exact description of the same, reference being had to the accompanying drawings, in which--

Figure 1 is a perspective view of a window with our improvement applied thereto. Fig. 2 is a side elevation of the attachment in its extended form. Fig. 3 is a similar view in the folded form.

Our improvement relates to that class of fire-escapes in which a jointed frame is attached to the window-casing, capable of being projected outward for the attachment of a rope, wire, ladder, or other device, by which a person may descend without coming in contact with window sills or cornices; or of being folded up in compact form at the sides of the window, and without obstructing the window, as hereinafter more fully described.

The invention consists in the combination of a wire forming a square loop pivoted to the sides of the window-frame and two side wires forming angular braces, also pivoted to the sides of the window-frame at the bottom, and provided with eyes at their top, which slide upon the sides of the upper wire, the arrangement being such that the frame can be folded upward and rest out of the way in the rabbets of the window-frame, or can be extended to support the rope, the eyes in that case striking the front of the upper wire and sustaining the parts.

In the drawings, A shows the upper wire, which is simply bent into square or rectangular form, consisting of the outer cross-length, a, and two side lengths, b b, the latter having eyes c c at their inner ends, which are pivoted to the sides of the window-frame.

B B are the two side wires that form the braces. At the lower end they have eyes d d, which are also pivoted to the sides of the window-frame, and at the top they have other eyes, f f, which are bent at right angles and

fit loosely upon the sides b b of the upper 50 wire, A.

The device, when extended, is of crane form, and substantially a right-angled triangle, as shown in Fig. 2, the upper wire being pivoted midway of the length of the window 55 and the lower wires pivoted at the bottom of the window. When the frame is extended, as shown in Figs. 1 and 2, a rope, wire, flexible ladder, or similar device, C, may be attached to the outer length, a, thereby enabling 60 a person to descend free of window-sills, cornices, &c., and the rope can be slipped laterally to any desired position the full length of said length a.

We are aware that various folding devices 65 are already in use on windows for the attachment of a rope and for throwing the rope out beyond cornices. Therefore we limit our claim to the particular combination of parts herein shown and described. This attachment being 70 all connected together, is opened or closed by simply turning one arm up or down. There is no adjustment of separate parts to be made. When the device is folded up, as in Fig. 3, the sides lie compactly in the rabbet of the window-frame, the cross-length being raised so high that it does not obstruct vision, and is not in the way. When lowered, the eyes of the braces slide on the sides of the main wire, and when the device is fully lowered said eyes 80 strike the cross-piece a, thereby forming a stop, which limits the movement of the frame, holds it in an extended position, and gives great strength and stiffness.

An awning may be readily attached to the 85 frame by attaching the upper edge of the awning to fixed hooks or clamps at the top of the window and the lower edge to the length a. The awning will then fold with the frame. A button or other device may be used for holding the frame in the folded position.

Instead of wire, as described, iron rod-round, square, or of other form in cross-section--may be used.

Having described our invention, what we 95 claim as new, and desire to secure by Letters Patent, is--

In a fire-escape, the combination of a wire,

A, forming a square loop pivoted to the sides of the window-frame, and two side wires, B B, pivoted at one end to the window-frame, and forming angular braces, the opposite end having eyes *ff*, which rest and slide freely on the sides of the wire A, said eyes connecting the parts so that they move all together, and forming stops to limit the movement of the frame in extending, as herein shown and described.

In witness whereof we have hereunto signed to our names in the presence of two subscribing witnesses.

GEORGE BORST.
FREDK. WILL.
